ATTORNEY

UNITED STATES PATENT OFFICE

HARRY B. ABEL, OF MACON, GEORGIA, ASSIGNOR TO NYE ODORLESS INCINERATOR CORPORATION, OF MACON, GEORGIA, A CORPORATION OF DELAWARE

FURNACE DOOR

Original application filed September 30, 1930, Serial No. 485,523. Divided and this application filed September 26, 1931. Serial No. 565,380.

This invention relates to furnace doors described and claimed in my co-pending application, Ser. No. 485,523 for incinerators, filed September 30, 1930, of which this application 5 is a division.

It has been proposed to line the walls of openings leading to furnace doors with metal plates but due to the intense heat the metal becomes warped with the direction of the warping being inwardly from the bricks or masonry and this warping often becomes so acute that the door openings are partially closed and thus obstruct the normal movement of the doors. The space provided by 15 the warping of the metal liners provides a passage for the flame and heated gas and a receptacle for clinkers so that the brick work or masonry is destroyed at this point.

An object of the invention is to provide a 20 door opening having the wall of the opening lined with metal in such a manner that the metal will not warp away from the masonry.

A further object of the invention is the provision of a door opening in which the walls 25 of the opening through the masonry or brick work are curved outwardly and lined with similarly curved metal plates so that the metal liner will tend to move outwardly rather than inwardly of the opening.

This invention will be best understood 30 from a consideration of the following detailed description, in view of the accompanying drawings forming a part of the specification; nevertheless, it is to be understood that the invention is not confined to the disclosure, being susceptible of such changes 35 and modifications which shall define no material departure from the salient features of the invention as expressed in the appended 40 claims.

Figure 1 is a vertical transverse section of a doorway constructed in accordance with the principles of my invention;

Fig. 2 is a vertical section in elevation 45 taken along the line 2-2 of Fig. 1;

Fig. 3 is a horizontal section taken along the line 3-3 of Fig. 1;

Fig. 4 is a view in elevation of the doorway from the inside of the furnace.

Referring more particularly to the drawings, 10 designates an upper opening and 11 a lower opening in a front wall 12 of the incinerator described and claimed in my co-pending application noted above. The walls 12 may be formed of fire brick or any other 55 material suitable for the purpose. It will be noted that the side walls 13 of the opening 10 are curved or bowed outwardly and a metal liner 14 which is curved in accordance with the curvature in the side walls 13 is applied 60 to the walls and maintained in place in any approved manner.

A keystone 15 formed of any suitable material is located at the top of the opening 10 and the inner face is curved as shown at 16. 65 A metal liner 17 neatly fits the curved inner surface 16 and conforms to the curvature of the inner upper face of the opening 10.

It will be noted from Fig. 3 that the side walls of the opening 10 and the metal liner 14 are bowed outwardly only at their inner edges next to the fire. The outer side edges are straight as shown at 27. This type of construction not only preserves the usual straight vertical sides of the door but makes the whole structure stronger and more rigid. The inner edges of the metal liners 14 which are exposed to sufficient heat to cause 70 ordinarily warping or buckling of the liners in this case retain their shape due to the curvature and direction of curvature of the liners. 80

A metal plate 22 forms a floor of the opening in passage 10 and is provided with a central opening 23 which is normally closed by a dead plate 24 hinged at 25 on lugs 26 depending from the bottom face of the outer portion of the floor or metal plate 22. 85

A door 30 is mounted for swinging movement at the outer end of the opening 10 for normally closing the opening or passage. 90

The inner end of the metal plate or floor 22 where the same projects into the furnace proper is provided with a depending lip 31 adapted to receive the outer end of a grate 5 not shown.

The opening 11 which leads into the ash pit of the incinerator is closed by a door 32 which is swingably supported in any approved manner and normally maintains the 10 passage or opening closed. The portion of the masonry, as shown at 33, has an inclined face 34 forming the bottom of the passage 11.

It is well known that in an incinerator the 15 opening or passage 10 provides means for agitating the material on the grate of the furnace and for removing clinkers or other matter which are undesirable in a furnace. This matter is raked outwardly until it rests upon the plate 24 and when this dead plate 20 is swung downwardly as indicated in dotted lines in Fig. 1 it will deposit the cinders and other matter upon the floor 34 of the passage 11 which leads into the ash pit.

The construction defined above with the 25 reference to the passage 10 shows the side walls of said passage bowed outwardly, and lined with metal while the upper wall is curved and also lined with metal so that when the temperature of the furnace becomes suff- 30 ficiently great to cause expansion of the metal liners 14 and 17 the metal liners will tend to bow in the direction of the curvature of the liners and thus prevent the liners from mov- 35 ing inwardly and tending to close the pas- 40 sage 10. Furthermore, these liners will main- 105 tain a tight fit with the curved side walls and thus prevent ashes, flame and hot gases from coming in contact with the masonry forming the curved side walls and top of the passage 10.

The upper edges and the lower edges of the metal liners 14 are located in substantially the same vertical plane. The front edges 27 of said liners are substantially straight 45 while the rear edges are curved as shown at 28.

The metal liners 14 and 17 form respectively 50 the side jambs and the top jamb. The curvature of the jambs 14 vary from the front to the rear or inner ends so that the greatest curvature of the jambs will be at their inner edges adjacent the fire chamber. In other words, the curvature of the concave side 55 jambs decrease from the rear or inner edges towards the front edges.

I claim:

1. In a furnace with masonry walls, a metal lined doorway having concave side jambs, the curvature of said jambs varying 60 from front to rear and the greatest curvature of each such jamb being at its rear edge.
2. In a furnace with masonry walls, a metal lined doorway having concave side jambs, the top edge of each jamb being in vertical 65 alinement with the bottom edge thereof.

3. In a furnace with masonry walls, a metal lined doorway having concave side jambs, the top edge of each jamb being in alinement with the bottom edge thereof, and the curvature of each jamb decreasing from the rear edge to 70 ward the front edge.

4. In a furnace with masonry walls, a metal lined doorway having concave side jambs, the curvature of each jamb decreasing from 75 the rear edge toward the front edge.

5. In a furnace with masonry walls, a metal lined doorway having concave side jambs, the curvature of each jam decreasing from the rear edge toward the front edge, and said front edge being vertical. 80
